UNITED STATES PATENT OFFICE

JAMES A. GAFFNEY, OF NEW YORK, N. Y.

BLADE HOLDER AND HANDLE

Application filed June 8, 1928. Serial No. 283,972.

This invention relates to a holder and handle for blades which is particularly designed for utilizing safety razor blades for other purposes after they have outlived their usefulness as a shaving medium.

While many devices of this nature have been devised and marketed, they have all been open to certain objectionable features and possess certain disadvantages. In order to meet with the various requirements which tend to render a device of this nature fully satisfactory in every respect, the same must first be inexpensive, and second easily or readily manipulated, both for the purpose of inserting and removing the blades or for completely separating the blade clamping portion to cleanse and remove accumulations or matter which collect between said portions. The clamping portions of said device must also be readily connectable after their separation and this without employing screws, bolts or other similar unnecessary and expensive parts which consume time on the part of the user in effecting the connection and disconnection.

The present invention meets with the above requirements and differentiates from devices which have preceded it, by the elimination of the objectionable features and disadvantages referred to.

The invention specifically comprehends an improved holder and handle for perforate safety razor blades which is completely formed from a single sheet of material to provide a pair of arms joined at one end by a curved connecting bight, the free end portions of said arms defining blade clamping jaws having interengaging means adapted to extend through the perforations of the blade and interengaging means at the juncture of the free end portions of the arms with the remainder of said arms for maintaining the jaws in parallel clamping relation, the said arms being so formed that pressure exerted thereon at a point between the connecting bight and their juncture with the jaws effects a limited relative separation thereof sufficient to allow for removal and insertion of the blades, without disconnecting and separating the arms.

With the above recited and other objects in view, reference is had to the following description and accompanying drawings, in which there is exhibited one example or embodiment of the invention, while the claim defines the actual scope of the same.

In the drawings:

Figure 1 is a perspective view of the blade holder and handle illustrating a blade associated therewith.

Figure 2 is a side view thereof.

Figure 3 is a similar view illustrating the manner in which the jaws are separated for insertion or removal of the blade.

Figure 4 is an enlarged transverse sectional view taken approximately on the line 4-4 of Figure 1.

Figure 5 is a sectional view taken approximately on the line 5-5 of Figure 1.

Referring to the drawings by characters of reference, the device is cut, bent and formed from a single sheet of resilient material to provide a pair of arms 10 and 11 joined at one end by a curved or substantially semi-circular bight 12. At their free ends, the arms are widened to provide a pair of blade clamping jaws 13 and 14, one of which jaws 13 is formed with openings or perforations 15 and the other of which jaws 14 is provided with up-struck or deformed portions 16 providing studs corresponding in size and shape approximately to the openings 15 in the jaw 13 and to the openings A in the perforate blade member B. The arms 10 and 11 are reversely curved from their juncture with the bight to the jaws with the convex inner surfaces in confronting relation. The inherent resiliency of the material from which the device is formed causes the arms to normally tend to separate. At a point substantially at the juncture of the arms with the jaws 13 and 14, the arm 11 is formed with an up-struck tongue 17 having a laterally projecting terminal 18, while the arm 10 is formed with an opening 19 of a size to snugly permit of the passage of the tongue therethrough when the arms are moved laterally out of alignment. After the passage of the terminal 18 of the tongue through the opening 19, the inherent tend-

ency of the arms to re-align themselves moves the edge 20 of the slot under the tongue terminal 18 to maintain the jaws 13 and 14 in substantially flat engagement with each other, while the portions of the arms having the tongue 17 and opening 19 inherently spring apart a limited distance due to the fact that the length of the tongue from its juncture with the arm 11 to its terminal 18 is greater than the thickness of the material from which the arm 10 is constructed.

Under this construction and arrangement, when pressure is exerted at a point intermediate the length of the arms to advance the arms toward each other to the position illustrated in Figure 3, the arms at the portions joined by the tongue 17 are first brought into engagement and with this as a fulcrum point further pressure on the arms effects a relative separation of the jaws 13 and 14 which is sufficient to dispose the inner surface of the jaw 13 above the free ends of the studs to allow for the insertion or removal of the blade B. When it is necessary to separate the arms and jaws for the purpose of cleansing the same to remove foreign matter collected thereon, pressure is exerted on the arms intermediate their length to initially cause the upper surface of the arm 10 to be disposed out of frictional engagement with the under surface of the terminal 18 of the tongue and to separate the jaws 13 and 14 sufficiently that the sides 16 will be out of contact with the openings 15, thus permitting lateral movement of the arms until the edge of the slot 20 is disengaged from under the terminal 18. It will thus be seen that in practice, with the blade in place between the jaws, the arms 10 and 11 together with the bight 12, form a convenient handle for using a discarded razor blade as a scraper or cutting implement for various other purposes than as a shaving medium, and that due to the interlocking engagement of the studs and openings 15 and the tongue and opening 17 and 19, accidental separation or release of the blade is precluded.

What is claimed is:

A blade holder for perforate blades, cut, bent and formed from a single sheet of resilient material to provide a pair of arms joined at one end by a curved bight, the free end portions of the arms defining laterally disposed blade clamping jaws, one of which is provided with integral studs and the other with apertures, said studs adapted to extend through the blade perforations and engage in the apertures of the other jaw, and integrally formed interengageable means at the juncture of the arms with the jaws comprising an upstanding tongue having a laterally projecting terminal upon one of said arms, said other arm having an opening of a size to receive said tongue for maintaining said jaws in clamping relation and for permitting a

limited relative separation of the same for the insertion and removal of a blade, by pressure exerted on the arms between their opposite ends, said interengageable means permitting of disengagement by pressure exerted on the arms and lateral movement of the same with respect to each other.

Signed at College Point, in the county of Queens and State of New York, this 28 day of May, 1928.

JAMES A. GAFFNEY.
